(57) **CLAIM**

The ornamental design for the cup elements of a brassiere, as shown and described.

DESCRIPTION

FIG. 1 is a perspective view of the cup elements of a brassiere as seen from the top, front and left sides showing our new design.

FIG. 2 is a top plan view thereof;

FIG. 3 is a front elevational view thereof;

FIG. 4 is a bottom plan view thereof;

FIG. 5 is a rear elevational view thereof; and,

FIG. 6 is a right side elevational view thereof, the left side elevation being a mirror image.

The broken line disclosure in the various views is for environmental purposes only and does not constitute a part of the claimed design.
